CLAIM

The ornamental design for a window component extrusion, as shown and described.

DESCRIPTION

FIG. 1 is a top perspective view of a first embodiment of a window component extrusion showing my new design.

FIG. 2 is a bottom perspective view thereof.

FIG. 3 is a top perspective view of a second embodiment of the window component extrusion showing my new design; and,

FIG. 4 is a bottom perspective view thereof.

(Continued)

The window component extrusion is shown with a symbolic break in its length. The appearance of the window component extrusion between the break lines forms no part of the claimed design.
